UNITED STATES PATENT OFFICE.

STEELE F. GILMORE, OF INDIANAPOLIS, INDIANA.

ANCHORAGE FOR DENTAL BRIDGES AND PLATES.

1,320,133.

Specification of Letters Patent. Patented Oct. 28, 1919.

Application filed August 11, 1919. Serial No. 316,741.

To all whom it may concern:

Be it known that I, STEELE F. GILMORE, a citizen of the United States, and a resident of Indianapolis, county of Marion, and State of Indiana, have invented a certain new and useful Anchorage for Dental Bridges and Plates; and I do hereby declare that the following is a full, clear, and exact description thereof, reference being had to the accompanying drawings, in which like numerals refer to like parts.

This invention is for an improvement over what is set forth in my former Letters Patent No. 1,022,070, issued April 2, 1912.

15 The object of this invention is to make the anchorage for dental bridges and plates more secure, so that the same will last much longer than is the case in the construction set forth in my former patent.

20 The chief feature of the invention relates to the construction of the clamping plate and particularly in vertically splitting the same so as to provide a number of clamping tips, and thus enable one to utilize a portion of 25 the clamping plate at one time, and after it is worn out to use another portion and thus prolong the life and the usefulness of the bridge or plate, for as soon as the clamp shown in my prior patent loses its resiliency 30 it makes it necessary to go to the expense of obtaining a new plate or bridge.

The full nature of the invention will be understood from the accompanying drawings and the following description and 35 claim.

In the drawings Figure 1 represents half of 40 the upper jaw showing some of the natural teeth out at one side, and showing a short round anchor bar secured to one of the remaining teeth. Fig. 2 is an occlusal view of the plate. Fig. 3 is the same as Fig. 1 with the plate shown in Fig. 2 in place. Fig. 4 is a perspective view of the plate showing the inside thereof with the metal clamp secured 45 in place. Fig. 5 is a perspective view, on an enlarged scale, of the clamp and a portion of the bar. Fig. 6 is a plan view of the clamp before it is put in the plate. Fig. 7 is a side elevation of the same. Fig. 8 is 50 an end elevation of the same. Fig. 9 is an end elevation of what is shown in Fig. 5, the bar being in section. Fig. 10 is the same as Fig. 9 with one of the clamping tips

broken away, and the other clamping tip being in use.

There is shown herein a plate 10 showing two false teeth secured to it and being adapted to fit on the jaw 11, as shown in Fig. 1. An anchor bar 12 of metal is secured to the tooth 13 by capping the tooth with gold in the usual way. The bar 12 is preferably, but not necessarily round and extends longitudinally of the gums and is employed for securing the plate 10 in place and so it can be removed.

The plate 10 has in the recess 14 in its inner side a clamping member 15 made of metal to clamp on the bar 12 when the plate is put in place as seen in Fig. 3.

The clamp 15 has a body portion which is substantially trough-shaped, of suitable size to receive the bar 12. On one side it has a substantially vertical side wall 16, and from the ends of said wall wings 17 extend, which are embedded in the plate 10 for anchoring the clamp to the plate.

The side of the clamp 15 opposite the side wall 16 is vertically split at 18 to form two 70 form two tips 19. Said tips are made of resilient metal which can be bent into the desired position and will yieldingly remain in said position. After the clamp has been secured to the bridge one of the tips 19 is bent inward somewhat as shown in Fig. 9 sufficiently to permit the clamp to be pressed 75 over and upon the bar 12 and to spring partially around said bar after the clamp has been pressed in place and thus hold the bridge 10 in position, excepting when the bridge or plate is forcibly removed.

The remaining tip or tips 19 are preferably left unbent and in a position substantially parallel to the side walls 16 to be bent into clamping position when the first bent tip loses its resiliency after use or becomes 80 broken, as shown in Fig. 10. Preferably in the arrangement illustrated the tip 19 nearest the tooth 13 is sprung into engagement with the bar 12 when the bridge is first made and fitted into place. Afterward when said tip 100 loses its resiliency, or the bridge or plate becomes loose or more worn, the tip more remote from the tooth 13 can be utilized for grasping the bar 12 for holding the bridge or plate in position.

My invention is capable of various appli-

cations to either the upper or lower jaw and to any form of anchor bar 12 or bridge 10 which may be required, the form shown in the drawings being merely for the purpose 5 of illustrating the nature of the invention.

The invention claimed:—

An anchorage for dental bridges including the combination of a bar anchored to one or more of the natural teeth, a plate having a channel to receive the bar, and a spring 10

clamp secured to the plate in said channel and having the clamping portion thereof split to form a number of tips any one of which is adapted to be bent in position to partially envelop and clamp the bar and yet 15 permit removal of the bridge plate therefrom at will.

In witness whereof I have hereunto affixed my signature.

STEELE F. GILMORE.
